BOX STRAPPING MACHINE

Parvin Wright, Seattle, Wash., assignor, by
mesne and direct assignments, to Acme Steel
Company, Chicago, Ill., a corporation of Illi-
nois

Application November 30, 1935, Serial No. 52,376

18 Claims. (Cl. 100—31)

This invention relates to bundle, or box, binding machines, and it has reference more particularly to machines for the application of metallic binding straps, bands, or the like, to boxes, bundles and packages; it being the principal object of the invention to provide a machine wherein means are provided for clamping a box in position for binding; for advancing the band or strap endwise, from a source of supply, about the box in a manner to cause the end, after the band has encircled the box, to be overlapped with a portion thereof leading to the supply; for securely holding the advanced end of the strap while the slack is removed and the band placed under tension about the box; for applying a sealing clip to the overlapped portions of the strap and means for severing the strap to free the bound bundle for removal from the machine while that end of the strap leading to the supply remains threaded into the machine, in readiness for the next binding operation.

Another object of the present invention is to provide a bundle binding machine of the character and employing the means above recited, that is fully automatic in its operations and which will accommodate boxes or bundles of various size, within the limits permitted by the machine, and without necessitating change in adjustment of its band applying means.

Other objects of the invention are to be found in the details of construction and combination of its parts, and in their mode of operation, as will hereinafter be fully described.

In accomplishing the objects of the invention, I have provided the improved details of construction, the preferred forms of which are illustrated in the accompanying drawings, wherein—

Fig. 1 is an elevation of a box strapping machine embodied by the present invention, showing a box located on the table, ready to be clamped for application of a binding strap.

Fig. 2 is a detail, in elevation, of the box clamp rod and clutch, as seen when looking in the direction of the arrow *a* in Fig. 1.

Fig. 3 is a detail of the gearing for making adjustment of the box clamping means when changing over from boxes of one size to another size.

Fig. 4 is an enlarged elevation of parts of the trigger mechanism in "set" position, the band gripping and clip applying means and associated parts shown in position just prior to actuation of the trigger mechanism.

Fig. 5 is a detail, showing the trigger after being actuated to "release" position and showing

the band end as held by the grippers during the tension applying operation.

Fig. 6 is a cross sectional detail of parts shown in Fig. 4, as seen on the line 6—6 in Fig. 4.

Fig. 6a is a detail of the band cutter mechanism.

Fig. 7 is an enlarged elevation of parts, as shown in Fig. 1, particularly showing the band feeding rolls and the band tensioning bar and its grip dog.

Fig. 8 is a detail of the band tensioning bar and dog and its actuating means.

Fig. 9 is a plan, or top view of the parts shown in Fig. 8.

Fig. 9a is a cross section on line 9a—9a in Fig. 8.

Fig. 10 is a plan view of a part of the machine showing the driving motor, the transmission gearing and the driving clutch for the clip applying and band cutting device.

Fig. 11 is a cross sectional detail showing parts as seen on section line 11—11 in Fig. 10.

Fig. 11a is a detail of the clutch mechanism.

Fig. 12 is an end view, partly in cross section of the driving and reversing gearing as seen on line 12—12 in Fig. 10.

Fig. 13 is a cross section on line 13—13 in Fig. 12.

Fig. 14 is a plan, or top view of a part of the machine.

Fig. 15 is a sectional detail through a portion of the band guideway and illustrating the band guide fingers and the means whereby they are retracted for application of a clip to overlapped parts of the band.

Fig. 16 is a cross section on line 16—16 in Fig. 15.

Fig. 17 is a view diagrammatically illustrating the clutch shifting and release means associated with the main clamp lever.

Fig. 18 is a top view illustrating the clutch shifting bell crank and parts connected thereto as seen when looking in the direction of arrow *b* in Fig. 17.

Fig. 19 is a detail of parts of the clutch shifting and clamp release devices.

Fig. 20 is a detail of the gripper jaw actuating and locking means.

Fig. 21 is a cross sectional detail, on line 21—21 in Fig. 20.

Fig. 22 is a cross section on line 22—22 in Fig. 20.

Fig. 23 is an enlarged, cross sectional view, as seen on line 23—23 in Fig. 4, of the seal applying and clinching means.

Fig. 24 is a front view of parts of the same during the application of a seal to overlapped ends of a strap.

Fig. 25 is a perspective view of one of the seals or clips before application.

Fig. 26 is a front view of the seal storage magazine.

Fig. 27 is a cross section as seen on line 27-27 in Fig. 26.

Fig. 28 is a perspective view of a seal as applied to overlapped ends of a band.

Fig. 29 is a wiring diagram for control of the motor.

Fig. 30 is a cross sectional view on the line 30-30 in Fig. 4 illustrating the mounting of the band gripping jaw levers.

The present machine, briefly described, comprises a table for supporting a box, and means for clamping the box against the table top while a strap is being applied thereto. That movement of the clamping means which sets it against the box is arranged to automatically set the machine in operation thereby to cause a strap, or band, to be fed between friction rolls into a guide-way by which the strap is guided about the box and opposite ends brought into an overlapped relation. After the moving strap has thus encircled the box, its advanced, or initial end engages and actuates a trigger mechanism whereby gripper jaws are moved to grip and hold the strap end and a clutch is shifted to cause reversal of the direction of the feed rolls so that the slack of the strap is taken up and the band placed under additional tension about the box. Then the seal applying means is actuated to apply a seal to the overlapped parts of the band, and a shear is actuated to cut the strap adjacent the clip thereby to free the bound box for removal from the machine. The final operation of the machine is to automatically trip the box clamp and to throw the machine out of gear and in readiness for receiving another box.

Referring more in detail to the drawings—

In its present preferred form of construction, the machine comprises a rectangular, supporting frame structure having vertical legs or uprights 1 at its four corners, joined rigidly across their lower ends by longitudinal bars 2 and by transverse bars 3, and likewise joined, across their upper ends, by longitudinal bars 4 and cross bars 5. This base frame structure forms a support for the binding mechanism, as will presently be described, and it also mounts, at one end, a pair of transverse angle bars 6-6' between which a plurality of parallel conveyer rolls 7 are rotatably mounted providing a table for easy conveyance of boxes into and from binding position.

Fixed vertically within the base frame structure is a tubular guide or standard 10. This is fixed at its lower end on a cross plate 11, supported by and fixed to the longitudinal bars 2. At its upper end the standard is fixed by an embracing strap 12 to the angle bar 6' and is thereby rigidly fixed in upright position. Telescopically movable in the guide 10 is a post, or extension 13. This extends from the upper end of guide 10 and, at its upper end, has a horizontal bed plate 14 rigidly fixed thereon which is the mounting bed for practically all of the operating or moving mechanisms. This bed plate extends at one side of the post transversely across the roller table, as best seen in Fig. 1, and at the other side of the post, it is extended sufficiently for the mounting thereon of an electric motor and the transmission gearing; the motor 16 being supported from the bed plate

14 by a bracket 15 and being disposed axially in the longitudinal direction of the plate.

As will be best understood by reference to Figs. 1 and 10, the drive shaft 16a of the electric motor 16 extends into a gear housing 17 and is equipped therein with a worm 18 which drives a relatively large worm wheel 19 fixed on a cross shaft 20 that is revolvably supported in bearings 21-21 in opposite walls of housing 17. This shaft 20 extends forwardly with reference to the showing in Fig. 1, through the housing wall, as shown in Fig. 12, and at its outer end is revolvably in a supporting bearing 22 on the base plate. Fixed on the shaft 20, within housing 17 and adjacent gear 19, is a gear wheel 25 meshing with and driving a smaller gear 26 fixed on a cross shaft 27 located parallel with and directly below shaft 20, and substantially co-extensive therewith. The shaft 27 is revolvably mounted at one end in bearings 28 in the gear housing walls and, at its other end is revolvably in a bearing bracket 29 fixed to the under side of bed plate 14 and below the bearing 22.

Freely revolvble on the cross shaft 20 near the bearing 22, is a gear wheel 30 that is fixed to, or is integral with, a band feed friction wheel 31 of the same size but spaced slightly therefrom, as seen in Fig. 12. The gear wheel 30 meshes with and is adapted to be driven in opposite directions by a larger gear wheel 32 that is revolvble on the cross shaft 27 and attached to or integral with a friction wheel 33 also revolvble on shaft 27 and disposed in alignment with the friction wheel 31 to coact therewith in the feeding of the box binding strap into the machine and for retracting it in removal of slack from an applied band. The feed friction wheel or roll 33 has a flat based, annular peripheral groove or channel 33a within which the friction wheel or roll 31 projects. This groove also serves as a guide for the band to prevent its displacement from between the friction wheels.

The supply of strap, or binding band material preferably would be wound on a reel, as designated at 35 in Fig. 1, which reel is revolvably supported on an axle 36. The band 38 is drawn off the reel and is fed into the machine by the action of, and between the friction rolls 31 and 33. Also, the band, after being placed about a box, is retracted by action of the rolls 31 and 33 to remove all slack therefrom, and this is incident to the reversal in direction of rotation of the friction rolls.

It will be best understood by reference to Figs. 12 and 13 that the friction rolls are driven in one direction or the other through the mediation of a shiftable clutch collar 40. This collar is keyed on shaft 27 and is shiftable longitudinally on the shaft. The collar 40 has clutch teeth 41 and 41' at its opposite ends. In one position, as seen in Fig. 12, the teeth 41 engage with opposingly facing teeth 42 on the hub portion of a gear wheel 43 that is fixed to or is integral with the friction wheel 33, thus to drive the friction wheel 31 in a direction for advancing the band 38 into the machine.

When the clutch collar 40 is shifted to its other extreme, its teeth 41' engage with opposingly facing teeth 44 on the hub of a gear wheel 45 revolvably mounted on shaft 27 adjacent gear 26. Thus, the driving of gear wheel 45 is only through the mediation of the clutch collar. Revolvably supported in bearings 46-46', depending from the plate 14 above the clutch, is a short shaft 47, which, at its opposite ends has gear wheels 48 and 49 fixed thereon. These gears mesh respec-

tively with the gear wheels 43 and a gear 43a on a supporting shaft 43b. Gear 43a, in turn, meshes with the gear 45, as seen in Fig. 13. Thus, when clutch collar 40 is shifted into engagement with teeth 44 to drive gear 45, this effects the driving of the friction roll 33 through the gear 43a, 49, shaft 47, gear 48 and gear 43, and since friction roll 33 also drives the gear 32 and this, in turn, drives gear 30, the friction roll 31 will thereby rotate and coact with roll 33 to retract the strap that has been fed into the machine. Briefly stated, the clutch collar shifted to one position, causes the binding strap to be fed into the machine. In its other extreme position, it causes the band to be withdrawn from the machine to take up the slack in a band placed about a box. The means for shifting the clutch collar 40 to these different positions operates automatically and it will be subsequently described in detail.

The position of the bed plate 14, spaced above and extending across the roller table, and mounted by the post 13 makes it available as a means for clamping the boxes against movement during a strapping operation. It will be observed by reference to Fig. 1, that there is a coiled spring 50 contained within the tubular post 13 which supports the bed plate 14 and that the lower end of this spring, which is under compression, rests against a support 51; the latter being extended through a longitudinal slot 52 in the post 10 and fixed for support at its outer end to a rack bar 53. This rack bar is extended parallel with the post and at its upper end is guided in mesh with a gear pinion 54 fixed on a horizontal shaft 55 revolvably mounted beneath the table in supporting bearings 56. An adjusting shaft 57 extends to the side of the machine, see Fig. 1, and is there equipped with a crank 58 while at its inner end it is equipped with a worm 59 meshing with a worm wheel 60 fixed on shaft 55. Rotation of the crank shaft 57 causes an upward or downward adjustment of the rack bar, and a corresponding raising or lowering of the post 13. It will be observed also that the lower end of post 13 terminates at a point spaced from the support 51 and this, by reason of the compressibility of the spring 50 permits the plate 14 to be pulled downward and clamped against a box, provided the two are reasonably close together and without making adjustment by means of crank shaft 57. It is to be understood that the crank shaft adjustment is to take care of that adjustment necessary when changing over from one size of box to another that can not be taken care of in the clearance between the lower end of post 13 and the support 51. Upon the completion of a binding operation, and release of the clamping plate, presently described, the spring 50 raises the post 13 and bed 14 to a position to free the box; this requiring only a slight upward movement of the bed.

When the bed plate 14 is in its raised position, as in Fig. 1, a box or the like, designated at B 65 may be moved into position on the roller table to receive the band or strap. After the box has been located on the table, the clamping operation is effected by the following means:

Pivottally attached at its inner end to the lower portion of post 10, is a foot lever 65 extended to the side of the machine and there equipped with a foot plate 66. This lever, at a point near its outer end, has a short link 67 pivotally attached thereto by bolt 68. A second lever 69 is pivotally attached at its inner end, by a pivot

bolt 70, to the lower portion of rack bar 53, and at its outer end this lever 69 is pivotally connected by bolt 71 with the link 67; this link being provided at intervals therealong with holes 72 to receive the bolt 71. Attached to the under side of the bed plate 14 is the strap guideway 75. This is in the form of an upwardly opening U-shaped rail, disposed in a vertical plane parallel with the direction of extension of bed plate 14, and provided at the ends of its two leg portions with flanges 75a-75b whereby it is secured rigidly to the bed plate.

Attached to the lower portion of this band guideway 75, are the upper ends of a V-shaped yoke 77. A bolt 78 is pivotally attached, at its lower end, by pivot 79, to the lever 69 with the upper end portion of the bolt extending slidably through an opening 80 in the yoke base. A coiled spring 81 is mounted about the upper end portion of the bolt to bear against a nut and washer 20 assembly 82 at the upper end of the bolt and against the yoke base.

Thus, when the operator actuates the lever 65 downwardly by stepping on plate 66, he causes lever 69 to be moved accordingly and this, by reason of the connections described, causes the bed plate to be pulled down and tightly clamped against the top of the box. It will be understood that in this operation of clamping the box, the spring 50 yields to the extent necessary. Furthermore, the spring 81 yields after the necessary clamping pressure has been placed on the box.

After the bed plate has thus been brought down against the box, it is necessary to hold it there until the completion of the binding or strapping operation. For this purpose a vertical clutch rod 83 is fixed at its lower end in the base frame and extends at its upper end portion through an aperture 86 through one end of a clutch plate 87 fixed to and overlying the end of the bed plate.

This clutch plate, as shown best in Fig. 2 is permitted a slight upward and downward movement at the end through which the rod 83 extends by reason of pivotal attachment pins 88 through its opposite end portion. By reference to Fig. 2 it will be observed that the attached end of plate 87 is spaced above the plate 14 by reason of a spacer 89, and it will be observed that the diameter of the opening 86 is such that the rod 83 cannot slide freely through it except when the plate is perpendicular thereto. Also, it will be observed that there is a bolt 90 extended through an aperture 91 in plate 87 and fixed in bed plate 14 and that a coiled spring 92 is mounted about the upper end of the bolt and bears downwardly against the plate 87 to hold it normally in a position at which it will effect a tight grip on the rod 83. Therefore, when the bed plate 14 is pulled downwardly, the clutch plate 87 will slide freely down rod 83, but should it start to move upwardly, a gripping action of plate 87 is immediately effected on rod 83 thereby to hold the bed plate 14 in clamping position. Release of the clutch plate is effected at the time of completion of a binding operation and this will be subsequently described.

Before describing the binding operation, it is desired to call attention to the fact that the band guideway 75 is of such dimensions that it will surround the box, and that in positioning a box on the table, the box is so located that the place at which it is desired the band shall be placed, will be in the plane of the guideway.

Assuming that a box has been placed on the table and that it has been clamped by manual actuation of the bed plate 14 downwardly against its top surface; the binding, or strapping, operation proper then starts, and the mechanism which effects this operation is automatically set into motion by the action of and coincident with the clamping operation.

By reference again to Fig. 1, it will be observed that a vertical link 38a is pivotally attached at its lower end to the outer end of lever 69. The upper end of this link is pivotally attached to a lever arm 93 which is pivotally mounted by a bolt 94 revolutely mounted in the upper portion 15 of a housing and bracket 95 that is fixed upon the bed plate 14. The lever arm 93, as shown in Fig. 4, has a stud 97 extended therefrom, and this stud is adapted when the arm 93 is swung downwardly, to engage and actuate the control slide 20 98 of a switch 99, thereby to close an electric circuit to be closed through the motor to set the machine in motion. The resetting of the switch slide 98 to open the circuit is effected at the completion of a cycle of operation as will later be described.

Assuming now that the end of the binding strap 38 has been threaded between the two friction feed rolls 31 and 33 and that the box B has been located in position on the table and has 25 been manually clamped by the bed plate incident to depressing the foot lever 65, and that also incident thereto the lever arm 93 has been actuated downwardly and has closed the switch 99 and the motor started, the strip 38 will then be advanced by the feed rolls for encircling the box. First, however, it is necessary to shift the clutch collar 40 into driving engagement with the teeth 42. This is effected as follows: Fixed to the 30 mounting end of the lever arm 93, is a downwardly depending arm 100, seen in Figs. 17 and 19, which is arranged to engage with and move a slide 101 mounted on guide rods 102 which, in turn, are supported at their ends in a bracket 103 fixed to the bed plate 14. When this slide 35 is thus shifted to the left with reference to Fig. 19, it engages at one end with the end of a clutch shift rod 105 and causes an endwise movement of the latter. This rod, as is shown best in Fig. 17, is connected with one arm 106 of a bell crank 40 40 107. The other arm 108 of the bell crank overlies the clutch collar 40 and has a stud 109 extended downwardly therefrom into the annular encircling groove 40a in the collar. When the bell crank is actuated by the endwise shifting 45 of rod 105 under action of slide 101, it moves clutch collar 40 to a position at which the teeth 41 interlock with the teeth 42 and thus the feed rolls 31 and 33 are set in motion and the strap 38 is fed into the machine.

After passing from the feed rolls, the strap is guided within a flat tubular guide 112 toward the clip or seal applying position. From the end of this tubular guideway, the strap passes across the top of the box and is received between an 50 overlying guide plate 113, shown best in Fig. 4, and the top of bed plate 14. As the strap continues to advance, its initial end will be guided through a bed plate opening 114 and then into one end of the interior channel of the guideway 55 70 75 which encircles the box, and on emerging from the other end of this guideway 75, the end of the strap, designated at 38a in Fig. 4, will move into underlapped relation with that portion of the band, 38b, leading to the supply.

It will be here mentioned that the guideway

75 is channeled, as at 75c in Fig. 4, throughout its length and this channel opens to the inner face of the guideway for withdrawal of the strap. Also, the natural stiffness of the band or strap is sufficient to prevent its dropping out of the 5 guideway or buckling while it is being pushed therein to encircle the box.

After the advanced portion of the binding strap has completely encircled the box in its travel through the guideway 75, and its initial end has 10 come into underlapped relation with the end portion of the band leading to the supply, then this advance movement is stopped and the feed rolls are immediately reversed to remove the slack from the band, and to cinch it up tightly 15 about the box preparatory to applying a seal about the overlapped portions. The reversing of the feed rolls is incident to the shifting of the clutch collar 40 from the full line position of Fig. 12 to its other extreme at which its teeth 41' 20 engage with teeth 44 to drive the reversing gear 43a. Shifting of the clutch collar 40 and also the actuation of the holding jaws to hold the end of the strap while it is drawn taut about the box 25 is under control of a trigger mechanism which is best shown in Figs. 4 and 5.

The trigger mechanism comprises a trigger 115 pivotally suspended on the front face of the bracket or housing 95 by a pivot 115'. At the lower end of this trigger is a horizontally and forwardly extended foot 116 which underlies the top run 38b of the strap 38, but is extended to a position at which it will be engaged by the end portion 38a of the strap as it advances after encircling the box, in underlapped relation with the part 38b. This foot has a notch 116a, see Fig. 5, within which the end of the advancing strap will abut, thereby to actuate the trigger on its pivot to "release" position, as seen in Fig. 5.

As the end of the strap advances into position to contact with the trigger foot, it passes between open band gripping jaws 120 and 121. The jaw 120 is a projection from the lower end of a lever 122 that is pivoted at a medial point on a hub 123 extending through and revoluble in a bearing in the front wall of the bracket 95. The jaw 121 is a projection from a lever 124 overlying lever 122 and mounted on a pivot 125 that is extended from and is eccentric of pivot hub 123. These jaws, respectively, underlie and overlie the end 38a of the strap. The upper end of lever 124, which terminates below the upper end of lever 122 has a longitudinal slot 126 and a pin 127, fixed in the upper end of lever 122, extends into this slot thereby to cause an opening 50 and closing action of the jaws incident to a back and forth action of the upper end of lever 122; this being by reason of their eccentric mountings.

The trigger 115 is formed at the side adjacent the lever 122 with an upwardly facing shoulder 130. Likewise, the lever 122 is formed at one side with a downwardly facing shoulder 131. When the trigger 115 is "set", its shoulder 130 engages with the shoulder 131, thereby holding lever 122 in such position that the jaws 120—121 will be opened apart for the passage therebetween of the advancing end of the strap, as shown in Fig. 4. A leaf spring 133 is fixed to the bracket 95 and bears against the lower end of the trigger 115 to yieldingly urge and hold it in "set" position. Also, a coiled spring 134, under tension, is attached to a stud bolt 135 through the upper end of lever 122 and to a bolt 136 in the bracket, thus to pull the levers when released by the trigger. 75

to that position at which the jaws will be caused to tightly grip the strap between them.

It will here be stated that the trigger is "set" incident to the clamping action of the bed plate. 5 When the foot lever is depressed, it pulls down on rod 93a, this actuates arm 93 downwardly to cause a short arm 138 fixed to pivot 94 to contact against the stud 135 and thus swings the lever 122 to a position that permits the trigger shoulder 130 to lock beneath the lever shoulder 131, thus to hold the parts set, the jaws open and spring 134 under tension.

Thus, it is apparent that, when the advancing end of strap 38 engages the trigger foot 116, it 15 will actuate the trigger to "release" position and the jaws, under tension of spring 134, will be actuated to grip and hold the end of the strap preparatory to reversal of the feed rolls and the 20 application of tension on the band to tighten it about the box.

It will be seen, by reference to Fig. 19 that the stud bolt 135, at the upper end of lever 122, extends rearwardly and through an arcuate slot 140 in the bracket 95, and, at the back side 25 of the bracket the stud is slidably contained in a longitudinal slot 141 of a latch arm 142. The latch arm is pivotally mounted on the bracket by a pivot 143 opposite the slotted end and at one side has a projecting shoulder 144 adapted to engage 30 with an opposingly facing shoulder 145 on the slide 101 to retain the latter at that position to which it was shifted, by action of the lever 100, on starting the machine.

When the trigger 115 releases the lever 122, and 35 the spring 134 actuates the lever 122 to close the gripping jaws against the initial end of the strap, this movement of lever 122 also, by reason of the bolt 135 extended into slot 141 of the latch arm, causes the latter to move pivotally on pivot 143 40 and its shoulder 144 to be disengaged from shoulder 145. This disengagement of shoulders releases the slide 101 and permits the shifting of the clutch collar 40. This will be understood by reference to Fig. 17 wherein it is shown that the 45 clutch shift rod 105 that is actuated by the slide 101, is guided through an apertured support 150 fixed to the base plate 14. Also, it is shown that, at a point spaced from the support 150, the rod has a collar 151 fixed thereon, and that a 50 coiled spring 152 encloses the rod and is held under compression between the support and collar. Thus, when the slide 101 is released incident to the tripping of the latch arm 142, it permits the rod 105 to be shifted under expansion of 55 spring 152, with a consequent shifting of clutch collar 40 to the position for effecting the reversal of the feed rolls 31 and 33. This reversal of the feed rolls effects the retraction of the strap and tightens the band about the box.

60 As the feed rolls, in reverse, cause the strap to be retracted, it is stripped from the guideway 18, by reason of the inwardly opening guide channel that extends its entire length, and it is then drawn snugly about the box. The friction of the 65 feed rolls on the strap, however, is not sufficient to draw the strap to the desired tightness, and, if it should be made sufficient for that purpose, it would be impractical to so apply it, in the present construction. Therefore, the tension 70 of the feed rolls on the band has been so adjusted that they will only draw the band up against the box to remove slack; then, a tension applying means takes effect on the strap to draw the band taut and to hold it while a seal is applied to the overlapped ends. This tension ap-

plying means will now be described with reference to Figs. 7, 8, 9 and 9a.

Disposed horizontally, to extend transversely across the motor driven cross shaft 20, is a band tensioning bar 160. This bar has an outer end 5 extension bar 161 of reduced width, which is slideable at its outer end in a support and guide 162.

At its inner end, the bar 160 has a downwardly extending plate 163 fixed rigidly thereto 10 and at the lower end of the plate, a band grip dog 164 is pivoted by a bolt 165. The lower end of this dog extends into the band guide channel 166 of a slide 167 and is pivotally attached to the slide by a transverse pivot pin 168. The guide 15 channel 166 is lengthwise of the slide 167 and opens through the opposite ends thereof, and the strap 38 in passing into the machine, is laid in this channel and normally slides freely between the lower end of the grip dog 164 and the channel 20 base. The slide also is slidably movable, in its longitudinal direction, within a guide slot 170 in the base plate 14 and is held in the slot by overlapping gibbs 171 fixed to the base.

It will be observed by reference to Figs. 8 and 25 9 that there is a latch bar 172 disposed adjacent and lengthwise of bar 160 and that it is connected at its left hand end with the bar 160 in a pin and slot connection; the pin 173 being fixed in bar 160 and extended through a longitudinal slot 174 in the end of bar 172. The free end of latch bar 172 terminates close to plate 163 and has a cam contact portion 172' at its upper edge extended above the top longitudinal edge of bar 160. Slidable on the bar extension 161, 28 and seated against the pivoted end of latch bar 172, is a collar 172b against which one end of a heavy coiled spring 175 presses. The outer end of spring 175 seats against a nut 176 adjustable on the bar to regulate the compression of the spring. Also, mounted on the bar 161, is a coiled spring 177 which bears at its opposite ends against the nut 176 and against the bar guide 162, thus to urge the bar 160 toward the left.

It will be observed by reference to Fig. 9 that 40 the end of the latch bar 172 which is engaged by the spring 175 is so shaped that the spring pressure thereagainst normally holds the free end of the latch lever somewhat above the level of bar 160, and this is for a purpose presently 45 described.

In the under edge of the latch bar 172 is a 50 notch or recess forming an abutment 178, and on the inner face of a spiral gear wheel 180 that is fixed on driven shaft 20 is a lug 181 that is 55 adapted during a period of rotation of wheel 180 to engage this abutment to thereby cause the bar 160 to be shifted lengthwise, and in a direction for shifting the bar 160 to place tension on the band which encircles the box.

It will be apparent, by reference to Fig. 8, that 60 with gear wheel 180 rotating in the direction of the arrow thereon, and with the latch bar 172 in the dotted line position shown, the lug 181 will engage the abutment and cause the shifting 65 of the bar 160. Thus, as the bar starts to shift, the pull on the grip dog through the pivot connection 165 will cause the dog to coact with the base of slide 167 to grip and hold the strap for the application of tension thereto.

The amount of tension that may be applied to the band is limited by the yielding of the coiled spring 175, and the tension of this spring may be regulated by adjustment nut 176. When the lug 181 disengages the latch bar abutment 70 75

178, the bar 160 is actuated back to initial position by the expanding of spring 171.

It is to be understood that the gear wheel 180 is continuously rotating, but it is not proper 8 that the tension bar 160 be actuated with each rotation, but only at a certain time. Therefore, the bar 172 is normally held in its raised position by the spring 175, as seen in full lines in Fig. 8, to not be engaged by the lug 181, so that normally no action of bar 160 takes place.

The spiral gear wheel 180 at all times is in driving mesh with a gear 187 of like kind and size, revolvable on a shaft 188 that overlies the bed plate 14 lengthwise thereof. The shaft 188 is revolvably supported at one end in a bearing 189 and at its other end in supporting bracket bearing 190 on the upper end of a bracket 191 that is fixed to base 14 at a location approximately medial of its ends. Fixed on this driven 15 shaft 188 is a cam 192 having a rise 192a adapted with each rotation of the cam to engage the cam contact portion 172' of latch lever 172, thereby to depress this latch lever to a position at which its abutment will be in position to be engaged 20 by the lug 181 on gear 180 for actuation of the bar 160. The shaft 188, when rotated, is revolvably driven by the gear 187, but only through the mediacy of a clutch collar 194 that is slidably keyed on shaft 188 adjacent the gear. As shown 25 in Fig. 11a, the collar has a spring pressed stud 195 in one end adapted to seat in a socket 196 in the face of gear 187 to thereby effect a driving connection between the gear 187 and shaft 188. The shifting of this clutch collar 194 toward 30 driving position is coincident with the shifting of collar 40 by means of the connections shown in Figs. 17 and 18, wherein 197 designates a clutch collar shift lever, pivoted at a medial point on the housing 17, by a pivot pin 198. One 35 end of the lever 197 terminates adjacent the side of the collar, and is equipped with a pin 199 extended into an encircling groove 200 in the collar to provide the clutch shifting connection. The other end of the lever is operatively connected by a yielding link 201 of a suitable kind with the 40 end of shift rod 105. This provides that, when clutch collar 40 is shifted into position to cause driving of the feed rolls 31 and 33 for advancing the band into the machine, the shifting means, at the same time, effects the shifting of collar 194 toward the face of gear wheel 187 but, for proper timing, it is temporarily restrained from 45 operatively connecting with the gear by means of a lever arm 205, see Figs. 10 and 11, which is disposed in a direction transversely of the shaft 188, and is pivotally fixed at one end as at 206, on the gear housing 17, and has its other end positioned to be pulled by a spring 207 between the face of gear 187 and the adjacent end of collar 194, thereby to hold them apart and the 50 stud 195 disengaged from the socket 196. In proper timing, however, a stud 208, which is set on the face of gear 187, engages the arm 205 and lifts its free end upwardly from the hub of collar 194, and the collar, being urged toward 55 the gear by the yielding link 201, causes the stud 195 to be seated in the gear socket 196, thereby effecting the driving connection which completes the driving connection for rotation of shaft 188.

As the shaft 188 rotates, it causes the cam 192 to operatively engage and depress the latch lever 172 into position for engagement by the lug 181 on gear 180, thereby effecting that movement of bar 160 whereby tension is placed on the box

band prior to applying the seal thereto. In the present instance, the effective travel of bar 160 is approximately one-half inch; if more, spring 175 absorbs it.

A sealing clip is applied to a band after the slack has been removed and tension applied, and just immediately before the tension bar is released by disengagement of lug 181 from the latch bar 172. The sealing clip is applied to the overlapped portions 38a and 38b of the band, but before it can be applied, certain conditions must be present which will now be explained.

By reference to Figs. 4, 15 and 16 it will be observed that the band, or strap, 38, as it is paid into the machine, is guided first over the jaws 121-120 and above the foot 116 of the release trigger. The guiding means consists of a pair of spring metal fingers 210-211 which continue beyond the end of guide tube 112. These fingers are substantially co-extensive, flat springs, disposed one on top of the other and fixed at their ends, which underlie the delivery end of guide tube 112, to a slide 212. The upper finger 210 has its free end portion curved upwardly toward the overhanging end of guide plate 113, thereby to cause the strap 38, when it is initially advanced, to be lifted over the grip jaw 121 and foot 116 and guided beneath the guide plate 113 into the guideway 75. Then, as the end of the strap, after passing about the box, comes out of the guideway 75c, it engages the under side of the finger 211 which is downwardly bowed, and it is guided thereby between the jaws 120-121 and into contact with the foot 116.

Therefore, before applying the seal, it is necessary to withdraw the fingers 210-211 from between the overlapped end portions of the strap, and it is also necessary to bring the overlapped portions flatly together.

By reference to Fig. 15 it is seen that the fingers 210 and 211 are fixed to a block 212 that is slidably movable in a guideway 215 in base 14 beneath the end of guide tube 112. This block is operatively connected by means of a link 216, with the lower end portion of a lever 217 that is pivotally attached at a point intermediate its ends as at 218' to a supporting bracket 218 fixed on base plate 14. A coiled spring 220 is attached to the lever 217 at a point below its pivot, and is fixed under tension to the bracket 191, thereby to move and yieldingly hold the lever in a position at which the fingers 210-211 will operate to guide the strap properly between the grip jaws. On the upper end of lever 217 is a cam roller 221 that is held, by reason of spring 220, against a cam 225 fixed on the shaft 188. This cam is timed to actuate the lever 217 to withdraw the guide fingers coincident with the setting of shaft 188 in rotation by the interlocking of clutch 194 with wheel 187. The guide fingers are held withdrawn until after the seal has been applied and the band cut, then the cam, by reason of its design permits the spring 220 to actuate the lever back to initial position, as seen in Figs. 4 and 15.

The seal applying devices and the means for lifting the lower end portion of the strap up against the upper portion, are shown in Figs. 23 to 27 inclusive. The kind of seal employed is shown in Fig. 25 and in Fig. 28 it is shown as applied to the band.

Referring to Fig. 23, it will be noted that the lapped ends of the band are parallel and one is spaced above the other. Extended below the lower end of the band are two parallel, spaced lift levers 226-226' which are pivotally movable on

supporting studs 229 fixed in a plate 230 which, in turn, is fixed to base plate 14. The rearward ends of these levers, when actuated downwardly will cause the forward ends to swing upwardly 5 against the lower strap and lift it up against the upper strap. While these parts are so held in contact, as shown in Fig. 24, the clip is applied thereto. The levers are actuated for lifting the strap by reason of contact with their 10 outer ends of a pivotally movable head 235, which, as shown in Fig. 23, is disposed transversely of and across the strap ends and is pivotally supported from its rearward end by a pivot bolt 236 fixed on a lug 237 on the rear edge of the 15 plate 14. This head 235, as presently described, carries the seal swaging jaws and is movable from and against the overlapped ends of the band.

The head 235 is provided in its under edge 20 with a transverse channel 238 within which the seals will be received from a feed magazine under action of a feed slide presently described. When received in this channel, the seals open downwardly and are supported between a pair of 25 seal clinching jaws 238-238'. When the head is subsequently actuated downwardly about its pivot 236, the overlapped ends of the band or strap are received in the channel and within the seal. It will be observed that the opposite side 30 walls of the seal are at this time open and outwardly inclined for easy application to the band.

The two jaws have pivotal supports 239-239' close to their ends, and have levers or actuating portions 240-240' extended upwardly therefrom 35 in diverging relation. Pivotally mounted in the head by a pivot bolt 241 at a point between the upper ends of the jaw actuating levers, is a main lever 242, and links 243-243' pivotally and operatively connect the upper ends of the jaw 40 levers, respectively, with the mounting head 242' of lever 242 at points opposite the pivot bolt 241. The lever 242 extends in a vertical plane transversely of the machine and along the face of a wheel 245 that is fixed on shaft 188. The wheel 45 has an eccentric stud 246 projecting from its outer face and this mounts a roller 246a that extends into and is movable along a longitudinal slot 247 in the lever 242.

A locking toggle, or elbow lever, comprising 50 two pivotally connected links 251 and 252 connects with the lever 240 of jaw 238 and with the pivot 236. This toggle, when straight or unbroken, operates to lock the jaws in open position and also, by reason of the connections with jaw 55 lever 240 and the connection of lever 240 with lever 242, locks the head 235 and lever 242 against relative movement. However, the toggle will be broken upwardly incident to the head being brought down to the position at which the overlapped portions of the strap are received in the seal. This breaking of the toggle is by reason of the engaging of a bolt 258 with the plate 14; the bolt being adjustably fixed in the toggle link 251.

Assuming the parts to be associated as 60 described, and in the position shown in Fig. 23, it is quite apparent that with the wheel 245 rotating in the direction of the arrow, the engaging of stud 246 against the lower end of the slot of lever 242 will cause the head 235 to be swung downwardly. This is by reason of the fact that the lever 242 is at that time held rigid with reference to the head 235 due to the position of the elbow lever comprising the links 251 and 252. As it reaches the position at which the strap ends 65 are seated in the seal, the roller 246 passes onto

the arcuate surface 265a of the cam rail 265, presently described, thus to hold the head down and the elbow lever comprising links 251 and 252 is broken upwardly by the contact of bolt 258 with the base plate. Then, farther rotation of 70 wheel causes the lever 242 to swing on its pivot 241 thereby to actuate the jaws together and against the sides of the seal to bend them beneath the under side of the band and to tightly clinch them to secure the strap ends together. 10

As the pivot stud 246 crosses the vertical central line of the wheel and again starts upward, it causes a quick swing of lever 242 to the left (with reference to Fig. 23) and this again opens the jaws and locks the toggle to hold them in 15 open position.

To insure the correct action of the lever and the return of the toggle to locking position while the pivot stud moves across the lower side of the circle from one side of the vertical center of the 20 wheel to the other side, a rail 265 is fixed to the top edge of the clinching head 235 and this has a part of its top surface arcuately curved as at 265a; the center of curvature being on the axial center of wheel 245 when the clinching head is 25 in its lowered, or clinching position. Incident to rotation of the wheel 245, the roller 246a on the stud 246 will come into contact with the top surface of bar 265 and will thereby cause the clinching head to be swung downwardly to the dotted 30 line position in Fig. 23. During the time that the clinching jaws are being actuated by the swinging of the lever 242, the roller 246a will be traveling along the arcuate surface of the bar 265, thus to hold the clinching head down in 35 position until after the clip has been applied and clinched to the overlapped ends of the band.

After the band ends have been sealed together, the end of the strap leading to the supply is cut at a point closely outside the seal. This cutting 40 of the strap is effected by means of a shearing blade 275 at the lower end of a lever 276 that is pivotally fixed, by a pivot 277 to a block 278 on the clip magazine. This blade transversely overlies the strap and operatively coacts with a fixed 45 shear plate 279 on the plate 14. The lever has a spring 280 attached thereto to normally hold the blade in open, or raised position. The lever extends into position to be engaged by a stud 281 projecting from the rear face of wheel 245 50 thereby to be actuated to cut the strap, thus to free the bundle for removal from the machine.

The seal feeding means comprises a vertical magazine or hopper 300 in which a pack of nested seals are located to feed downwardly by gravity. 55 On the lower end of the magazine is a guide 301 containing a feed slide 302. The slide is reciprocally movable to advance the seals, one at a time, from the magazine into a holder 303 attached to the side of the magazine. As seen in 60 Fig. 27, the slide 302 has a pin and slot connection as at 305 with a lever 306 pivotally fixed to a bracket 307 on the back of the magazine. A coiled spring 308, contained in a socket 309 in the bracket, acts against the lever 306 to move it 65 to a retracted position. An actuating lever 310 is pivotally supported by a pivot on the bracket 181 and this has a link 313 connecting it at its lower end with the slide 302 and at its upper end has a cam roller 315 engaging a cam 316 fixed 70 on shaft 188 which operates, upon the completion of each strap shearing operation, to advance one seal into the guideway 303. This pushes the next previously advanced seal from the guideway into the channel between the jaws of 75

the clinching head, preparatory to the next operation; it being understood that, when the seal clinching head is lifted, as seen in Fig. 23, it is then properly registered with the guideway 303 to 5 receive the advanced seal.

After the seal has been clinched and the strap cut, the box is then ready for removal from the machine, but in order to free it, the initial end of the band must be released from between the 10 grip jaws and the band must be pushed from the jaws and also from the other parts which it overlaps; for instance; the foot 116 and levers 228. These operations are effective as follows: Extended in an upright position adjacent the face 15 of the wheel 245 is a lever arm 320 fixed at its lower end to a supporting shaft 321 that extends horizontally and lengthwise of the bed plate and is revolutely mounted in supporting bearings on the fixed bracket 95 as seen in Fig. 19. The upper end of the lever extends into position at which it will be engaged and moved by the stud 246 extended from the face of wheel 245 thereby to rock the shaft 321 through a definite arc. Fixed on the inner end of the hub 123 which 20 mounts the jaw levers, is a horizontal cross plate 325, the opposite ends of which extend to opposite sides of the hub. This plate is held against movement during a band applying and tightening operation and during the clip sealing operation, 25 and thereby holds the grip jaws against loosening their hold on the initial end of the band. However, when it is finally desired to release the band end, the plate is released and the hub 123 is rotated thereby through an interval whereby the 30 pivot point 125 for lever 124 is elevated relative to the center of the hub and this lifts the grip jaw 121 to free the band end.

When the jaws are set against the band, as during a binding operation, the cross plate 325 40 is held against that jaw releasing movement by a latch 328 supported from bracket 95 by a pivot 329 and acted on by a spring 330 to yieldingly hold it in supporting position beneath the adjacent end of the plate 325.

45 When the lever arm 320 is rocked rearwardly by the movement of stud 246 on wheel 245, the shaft 321 is likewise rocked, and a short lever arm 335 fixed on the rock shaft engages the latch 328 and displaces it upwardly from supporting contact with the plate 325, permitting that end of the plate thus to swing downwardly. There is also a lever arm 336 fixed on the rocker shaft and this is arranged to engage and lift the opposite end of plate 325 after the release 50 by latch 328. This movement of plate 325 rotates the hub 123 and insures release of the grip jaws. Coincident with the release of the grip jaws, the band is "kicked out" from the jaws and free of the foot 116 and band supporting levers. This 55 is effected by means of a vertical lever 340 which is pivotally supported from bracket 95 by a pivot 341 as seen in Fig. 6. The lower end of the lever is disposed just back of the band and its upper end is connected by a link 342 with the lever 60 arm 320. Thus, when lever 320 is actuated rearwardly, it effects the "kick out" action of lever 340.

Simultaneously with the release of the band, the clamping action of the bed plate 14 against 70 the box is released. This is effected by means of a release arm 345 on the end of shaft 321 and with its end extended to a position immediately beneath the movable end of clutch plate 87. Therefore, when the shaft 321 is rotatably actuated, the arm effects that lifting action of the 75

plate that is necessary for and which results in the release of its hold on clutch rod 83, and the spring 50 then operates to lift the bed plate 14 upwardly to free the box. Simultaneously with the release action, the switch slide 98, is actuated 5 upwardly by an arm 350 on shaft 321 and this stops the motion of the machine.

The various parts associated with the jaw release plate 325 are brought back to normal position by pressure of a coiled spring 352 which is 10 set in a socket 355 in bracket 95 and bears upwardly against plate 325, as seen in Figs. 19 and 20.

Referring now to the wiring diagram, Fig. 29, it is observed that the main circuit wires 365— 15 366 connect with switch 99. A circuit wire 367 leads from the switch to one side of the motor. Two brushes 368 and 369 are disposed to contact with a circuit breaker fixed on shaft 188 and are connected respectively with the motor 16 and 20 switch 99. The circuit breaker comprises a cylindrical hub of non-conductive material coaxial of the shaft 188, and fitted with a metal sleeve 370 with a gap 371. This gap is so arranged that it effects the opening of the motor circuit at a pre-determined interval just before the end of a cycle of operation and this slows it practically to a stop. The momentum causes it to coast just far enough to again close the circuit between the brushes but during this open circuit interval, the 25 main switch will be opened. The purpose of the circuit breaker is to open the motor circuit at a time in advance of the completion of a cycle, that it will be slowed to a stop when the cycle is 30 completed. This time of opening the circuit may be varied as desired by rotatably adjusting the sleeve on the shaft 188.

Assuming that the parts are so assembled, the sequence of operation of the machine, briefly described, is as follows:

Assuming that the box B is placed on the roll table, depression of the foot pedal 66 and lever 65 effects the clamping of the bed plate 14 against the top of the box. Releasing of the clamping action is prevented by the locking of the clutch plate 87 with the rod 83. Coincident with this depression of the foot pedal and clamping of the box, the lever 93 is actuated downwardly to set the trigger mechanism and to close the circuit switch 99, thereby to energize the motor. This 40 action of the arm 93 also shifts the clutch collar 45 for driving the band feed rolls.

The band is advanced by the feed rolls along the guideway 15, and its advancing end portion finally trips the trigger thereby closing the grip 55 jaws against the end of the band and reversing the direction of the feed rolls so that slack is removed from the band. It is drawn tightly about the box and placed under tension.

Immediately following the application of tension to the band the seal applying mechanism is set in motion by the rotation of the shaft 188; a seal is applied and clinched about the overlapped ends of the band, and the shear mechanism operates to sever the strap closely adjacent the outside of the seal. Immediately following the severing of the band the "kick out" mechanism is actuated to remove the band from between the jaws and this is coincident with the 70 opening of the jaws, the opening of the switch circuit and the release of the clutch plate 87 from the rod 83. Opening of the circuit stops the operation of the motor and the release of the clutch plate permits the spring 50 to lift the 75

clamp plate free of the box for removal of the box from the machine.

Having thus described my invention, what I claim as new therein and desire to secure by Letters Patent is—

- 5 1. In a box strapping machine, a table, a bed plate supported above the table and having a downwardly yieldable mounting, means operable to adjust the bed plate downwardly against a 10 box placed on the table, thereby to clamp the box for strapping, and means mounted on the bed plate and operable to place and secure a strap under tension about the box.
- 15 2. In a box strapping machine, a table, a bed plate supported above the table and having a downwardly yieldable mounting, means operable to adjust the bed plate downwardly against a box placed on the table, thereby to clamp the box for strapping, a releasable clutch for holding the bed plate in box clamping position, means on the bed plate operable to locate and secure a strap under tension about a clamped box and means for automatically releasing said clutch upon completion of the strapping operation.
- 20 3. In a box strapping machine, a supporting table, a bed plate spaced above the table, a downwardly yieldable support for the bed plate, means for actuating the bed plate downwardly against a box on said table to clamp it for strapping, a guideway encircling the clamped box, means for advancing a strap endwise within the guideway, thereby to cause it to encircle the box and its advanced end to be overlapped with the opposite end of the box encircling portion, means for placing the strap under tension about the box, means for applying a seal to the overlapped ends of the box encircling band and means for severing the strap at the outside of the seal.
- 25 4. In a box strapping machine, a table, a bed plate spaced above the table and having a downwardly yieldable support, means for actuating the bed plate downwardly against a box on said table to clamp it for strapping, a clutch for holding the bed plate in clamping position, a guideway fixed to the bed plate and encircling the clamped box, driven feed rolls for advancing a strap endwise along the guideway to cause it to encircle the box and its advanced end to be overlapped with the opposite end of the box encircling portion, a gripper for receiving and holding the said advanced end, means for reversing the feed rolls to place the band under tension about the box, means for applying a seal to the overlapped ends of the band, means for severing the strap at the outside of the seal and means operable to release the clutch and gripper.
- 30 5. A machine as in claim 4 wherein an electric motor is provided for driving the feed rolls and devices are actuated by the box clamping means to start the motor, and devices operate incident to the release of the clamping means to stop the motor.
- 35 6. In a box strapping machine, the combination with means for holding a box for strapping and a reversible strap feeding means, of a guideway in which a strap may be advanced endwise by the feeding means to cause it to encircle the box and its advanced end to be overlapped with the opposite end of the box encircling portion, a gripper arranged to receive the advancing end of the strap after it has encircled the box, a trigger mechanism operable by the advancing strap end to effect an actuation of the gripper to grip the strap end and a reversal of the feeding means thereby to draw the band about the box, and
- 40 means for applying a seal to the overlapped portions of the band.
- 45 7. In a box strapping machine, means for supporting a box for strapping, a strap feeding means, a guideway encircling the box and in which a strap is advanced endwise by the said feeding means to place it about the clamped box with its advanced end in lapped relation with the opposite end portion of the box encircling band, a trip member positioned to be engaged by the end of the band, a gripper adapted to be released by the trip to grip the band end and to reverse the feeding mechanism whereby to place the box encircling band and the two end portions thereof under tension, and means for applying a joining seal to the overlapped portions thereof.
- 50 8. In a box strapping machine, means for supporting a box for strapping, a reversible strap feeding means, a guideway in which a strap will be advanced endwise by the said feeding means to encircle the box and locate its advanced end in lapped relation with the opposite end portion of the box encircling band, means for gripping the advanced end of the strap after the box has been encircled, means operable incident to gripping the strap end for reversing the strap feeding means for retracting the strap to displace it from the guideway and to place it and the overlapped end portions thereof under tension about the box, means for applying a holding seal to the lapped portions to secure the band under tension about the box and means for severing the strap at the outside of the seal.
- 55 9. In a box strapping machine, means for supporting a box for strapping, strap feeding means, a guideway in which a strap may be advanced endwise by the feeding means to cause it to encircle the box, a pair of open grip jaws arranged to receive the advanced end of the strap between them after it has encircled the box, means operable by the advancing end of the band to cause the jaws to grip and hold the band end, and to reverse the direction of the band feeding means thereby to draw the band from the guideway and about the box, means for applying a seal to the overlapped portions of the band and means operable, after the seal is applied, to cut the strap at the outside of the seal.
- 60 10. In a box strapping machine, means for supporting a box for strapping, reversible feed rolls operable in one direction for advancing a strap into the machine, a guideway in which the strap may be advanced endwise by said feed rolls to cause it to encircle the box, a pair of grip jaws arranged to receive the advancing end of the strap between them after it has encircled the box, a trigger mechanism arranged to be actuated by the advancing end of the strap to cause said jaws to be closed on the strap end and the feed rolls to be reversed, thereby to draw the band from the guideway and about the box, means for applying tension to the band and means for applying a holding seal to the opposite end portions of the box encircling portion after it has been placed under tension and means for cutting the strap adjacent the seal.
- 65 11. In a box strapping machine, a table, a bed plate supported above the table and having a downwardly yieldable mounting, means operable to adjust the bed plate downwardly against a 70 box placed on the table, thereby to clamp the box for strapping, a releasable clutch for holding the bed plate in clamping position, a guideway fixed to the bed plate to encircle a box on the table, and opening inwardly throughout its length to-

- ward the box, a reversible strip feeding means, operable to feed a strap endwise into said guideway to cause it to encircle the box, grip jaws arranged to receive the advanced end after it has encircled the box, a trigger mechanism adapted to be released by said advancing end after it has passed into the said jaws, to cause said jaws to grip and hold the advanced end, and to cause said strap feeding means to be reversed, to draw the strap from the guideway about the box, means operable to place the band under tension about the box, means for applying a seal to the band, and means for severing the strap adjacent the seal and for releasing said clutch and grip jaws.
12. In a box strapping machine, a box support, reversible feed rolls for feeding a strap into the machine, a guideway in which the strap may be advanced endwise to encircle the box and locate its advanced end in lapped relation with the opposite end of the box encircling band, a pair of open grip jaws arranged to receive said advancing end after encircling the box, a trigger mechanism, normally positioned to retain said jaws in open position, and releasably therefrom by said advancing end of the strap to permit the jaws to grip the strap end, means operable incident to actuation of said trigger to reverse the feed rolls to draw the strap from the guideway, while held by the jaws about the box, means for applying an added tension to the band after it has been drawn about the box, means for placing a holding seal to the lapped ends of the box encircling band while it is held under tension, means for cutting the band at the outside of the seal, and means for releasing said jaws for the band end and for displacing the band therefrom.
13. In a box strapping machine, the combination with means for advancing a strap endwise about a box, and means for receiving and gripping the advanced end of the strap after encircling the box, of a strap tensioning means comprising a shiftable bar, a grip dog mounted thereon, normally passing the band freely there-through, a shifting lever pivotally mounted on the bar and having an abutment shoulder, a rotatably driven member, a yieldable means normally holding the lever elevated out of path of travel of the rotatably driven member and means timed with the operation of the strap advancing means for depressing said lever to cause its abutment to be engaged by said rotatably driven member to actuate the bar for applying tension to the band.
14. In a box strapping machine, the combination with a seal applying means, a guideway encircling the box and terminating at the opposite side of the seal applying means in which a band

may be advanced endwise to encircle the box and its advanced end to be underlapped with the other end of the box encircling portion beneath the seal applying device and a band guide member bridging the gap beneath the seal applying means, of means for withdrawing the said guide member and means for elevating the lower band end against the upper portion for reception of the seal.

15. In a machine of the character described, a frame structure, a table thereon for mounting a box, a tubular standard fixed in the frame, a post telescopically movable in the standard and extending upwardly therefrom, a bed plate mounted by the standard to overlie the table, a box binding mechanism mounted by the bed plate, a coiled spring contained in the post and standard and acting against the latter to yieldably support the bed plate and to counterbalance the weight thereon, a foot pedal and means operatively connecting the pedal with the bed plate to clamp the latter against a box located on the table.

16. In a box strapping machine, the combination with means for applying a strap about a box and for overlapping its ends, and means for applying tension to the band, of means for applying a seal to the said ends of the band including a seal clamping head having seal closing jaws therein, means for placing a seal in the jaws, an actuating lever for actuating the head and jaws having a cam surface and a rotating member operable against said surface thereby first to actuate the head to position the jaws and seal about the band ends and then by a differential force to effect the closing of the jaws to apply the seal.

17. In a box strapping machine, strap gripping means comprising a pair of levers disposed longitudinally, one upon the other, and each pivotally supported intermediate its ends with the supporting pivots offset from each other in a direction transverse of the levers; said levers being provided at corresponding ends with cooperating grip jaws adapted to receive a strap between them and having their opposite end portions operatively connected whereby an oscillating action of one will be transmitted to the other to cause a relative closing or opening of the jaws, releasable means engaging one of the levers to normally hold the jaws open, and means under tension for actuating the levers to close the jaws when the said releasable means is released.

18. A gripper as recited in claim 17, wherein the gripping surfaces of the jaws are smooth and are curved to grip the band between them with a rolling action.

PARVIN WRIGHT.
